[57] CLAIM

The ornamental design for a bottle, as shown and described.

DESCRIPTION

FIG. 1 is an elevational view of a bottle embodying our new design, the opposite side being a mirror image thereof;

FIG. 2 is a side elevational view looking from the right of FIG. 1;

FIG. 3 is a side elevational view looking from the left of FIG. 1;

FIG. 4 is a bottom plan view thereof;

FIG. 5 is a top plan view thereof; and

FIG. 6 is a sectional view taken along line 6—6 of FIG. 1.
